COLLATING MACHINE

Logan W. Johnson, Minnetonka, Minn., assignor to Minnesota Mining and Manufacturing Company, St. Paul, Minn., a corporation of Delaware

Filed Oct. 21, 1969, Ser. No. 19,659

Term of patent 14 years

Int. Cl. D18—99

U.S. Cl. D64—11

FIG. 1

FIG. 2

FIG. 3

FIG. 4

FIG. 5

FIG. 6

FIG. 1 is a perspective view of a collating machine showing my new design;

FIG. 2 is a front elevational view;

FIG. 3 is a right side view;

FIG. 4 is a rear elevational view;

FIG. 5 is a left side view; and

FIG. 6 is a top plan view thereof.

The bottom not shown is substantially free of ornamentation.

I claim:

The ornamental design for a collating machine, as shown and described.
